C. T. RIDEOUT, OF BOOTHBAY HARBOR, MAINE.

Letters Patent No. 77,095, dated April 21, 1868.

IMPROVEMENT IN RUDDER-GEAR.

The Schedule referred to in these Letters Patent and making part of the same.

TO ALL WHOM IT MAY CONCERN:

Be it known that I, C. T. RIDEOUT, of Boothbay Harbor, in the county of Lincoln, and State of Maine, have invented a new and improved Rudder-Gear; and I do hereby declare that the following is a full, clear, and exact description thereof, which will enable those skilled in the art to make and use the same, reference being had to the accompanying drawings, forming part of this specification, in which—

Figure 1 is a deck plan exhibiting my improved gear.

Figure 2 is a removed section showing the same in elevation.

Similar letters of reference indicate corresponding parts.

The nature of this invention consists in the employment of a traversing-segment having teeth, which engage with the teeth of a disk keyed to the rudder-head, whereby the tiller can be made shorter, and take up less room in its travel across the deck, together with a device for securing the rudder in any desired position, as will be duly described.

In the drawings, A is the rudder-post, B the rudder. C is an iron sector, having a socket, T, for the reception of the tiller T'.

This sector is provided with teeth t upon its arc, and a strong bolt, b, pivots it to the deck.

Just behind this sector is the rudder-head A', on which is keyed a disk, C', of metal, generally of iron or bronze, provided with teeth t', of suitable length and pitch to engage, without backlash, the teeth t upon the sector C.

A circular adjunct, D, forms a part of the disk C', and in practice is cast upon it.

This projection D is provided with a central hole, h, and, by the action of the rudder, is vibrated over a metallic arc D', secured in the deck beneath it.

The hole h, in its arc of vibration, passes over a series of holes, h' h'' h''', in the said arc D', and can be brought immediately over and to coincide with any one of the said holes, as h' h'' h''', and a strong pin can be passed down through the hole h and into any one hole in the arc D'.

Thus the rudder will be held in a fixed position, and the tiller T' can be unshipped, if desired.

The rudder-head A' should extend far enough above the disk C' to admit a tiller shipped or set on in the ordinary way, if, by any accident, it should be required.

The rudder, geared as above described, can be operated with a simple tiller, or the latter can be provided with the usual wheel-ropes, blocks, and wheel, in connection with it, and in large vessels this would be desirable, though not necessary.

When at anchor, the rudder can be made stationary amidships by means of the pin through the projection D and the arc D', as before described, and the same means can be employed to keep the rudder hard-a-port or hard-a-starboard, or at any intermediate point when occasion requires.

This simplification of the gearing attached to rudders renders it an important improvement on the other gearing-devices heretofore known and used, all of such devices being a combination of three or more cog-wheels, working on shafts, and requiring a heavy frame for supporting the working parts, which are, from their complication, liable to accident.

These objections my improved gear obviates, and while it accomplishes fully the required movement in the rudder, the tiller traverses on a very short arc, thus enabling the helmsman to steer the vessel with ease and uniformity.

Being compact, simple, and strong, it is not liable to get out of repair, or subject to accident in heavy weather, and can be applied to any vessel at a very moderate expense.

I claim as new, and desire to secure by Letters Patent—

The combination and arrangement of the toothed sector C, having the tiller and socket T T', the toothed disk C', having projection D with hole h, and the perforated arc D', as herein described for the purpose specified.

C. T. RIDEOUT.
